UNITED STATES PATENT OFFICE

JOHN T. WELCH, OF DOWAGIAC, MICHIGAN

MASSAGING MACHINE

Application filed August 26, 1929. Serial No. 388,476.

The main objects of this invention are:

First, to provide a massaging or exercising machine which is very simple and compact in structure and at the same time powerful and durable.

Second, to provide a structure having these advantages which runs quietly and with a minimum of vibration.

Objects pertaining to details and economies 10 of my invention will definitely appear from the description to follow. The invention is defined in the claims.

A structure which embodies the features 15 of my invention is clearly illustrated in the accompanying drawing in which:

Fig. 1 is a side elevation of my improved massaging machine, the strap-like applicator being partially broken away and the machine being shown in anchored relation to a 20 wall.

Fig. 2 is a fragmentary plan view, a portion of the housing or gear box being removed.

Fig. 3 is a view mainly in transverse section 25 on line 3—3 of Figs. 2 and 4.

Fig. 4 is a fragmentary view mainly in longitudinal section on line 4—4 of Fig. 3.

In the embodiment illustrated the supporting standard 1 is formed of a piece of pipe 30 or tubing provided with a floor plate 2 at its lower end and a top plate 3. These plates have sockets 40 to receive the ends of the tubing. The base plate 4 is provided with supporting engaging lugs 5 adapted to enter 35 holes in the plate 3, and with spaced ears 6 adapted to receive the eye 7 of the screw 8 between them. The screw is threaded into the wall indicated at 9 and connected to the ears by the pin 10.

40 The motor 11 is mounted on the base 4. The base 4 is also provided with a gear box base 12 having bearings 13 and 14 for the driven shaft 15. The driving shaft 16 of the motor is supported in a bearing 17 on the motor housing. This driving shaft is provided with a driving pinion 18 meshing with the gear 19 on the shaft 15.

The gear 19 is preferably of fiber, raw-hide or other suitable material to eliminate noise 50 in the gears. This gear is secured to the

drum 20 by means of screws 21 and is secured to the shaft by means of the set screw 22. This arrangement permits the gear and drum to be assembled as a unit, dropped into the gear box and the shaft inserted. The set 55 screw is then inserted.

I preferably provide a bearing or thrust washer 23 between the gear and the adjacent end of the gear box.

The drum is provided with a continuous 60 worm or cam groove 24 disposed in a plane inclined to the axis of the drum.

The actuated member 25 is provided with a yoke-like bearing 26 coacting with this groove 24 so that as the drum rotates the 65 actuated member is oscillated. The yoke form of bearing permits ready assembling of the parts, although it will be readily understood that the drum might be made of two pieces should it be desired to make the bearing 70 26 continuous.

The actuated member 25 projects through slots 27 in the housing cap or top member 28 which is removably secured to the housing or gear box 12 by means of screws as 29. The 75 actuated member is provided with a series of annular grooves 30 at each end with which the applicator 31 may be selectively engaged, the applicator having key-hole slots 32 therein permitting selective engagement with the grooves 30 thereby determining the stroke of the applicator.

The base portion of the gear box is designed as a lubricant receptacle so that the parts may be efficiently lubricated.

The structure may be built in very compact form and is very powerful; that is, owing to the driving means for the actuated member it is practical to use motors of small horse power.

I have not attempted to illustrate or describe various modifications which I contemplate as it is believed that this disclosure will enable those skilled in the art to embody or adapt my improvements as may be desired.

Having thus described my invention what I claim as new and desire to secure by Letters Patent is:

1. In a massaging machine, the combination of a base plate provided with an integral 100

2

gear
shaft
box
